UNITED STATES PATENT OFFICE.

FRANCIS H. RICHARDS, OF HARTFORD, CONNECTICUT, ASSIGNOR, BY
MESNE ASSIGNMENTS, TO AMERICAN TYPOGRAPHIC CORPORATION,
A CORPORATION OF NEW JERSEY.

MOVEMENT-STARTING MECHANISM.

No. 823,081.

Specification of Letters Patent.

Patented June 12, 1906.

Application filed April 15, 1899. Renewed June 27, 1904. Serial No. 214,349.

To all whom it may concern:

Be it known that I, FRANCIS H. RICHARDS, a citizen of the United States, residing at Hartford, in the county of Hartford and State of Connecticut, have invented certain new and useful Improvements in Movement-Starting Mechanism, of which the following is a specification.

This invention relates to movement-starting mechanism, and especially to a mechanism adapted for starting the rotation on its axis of an orbitally-movable wheel—such, for instance, as a type-wheel or in general a wheel carrying impression devices—and is particularly adapted for use in connection with a certain class of key-operated mechanisms—such, for instance, as that described in my prior patents, No. 401,371, granted April 16, 1889, and No. 573,620, granted December 22, 1896.

My present invention may be embodied advantageously in a mechanism substantially of the type illustrated in such last-mentioned patent in which I have shown a rotatable and normally revolving driven gear, which by means of suitable devices is carried into and out of engagement with a driving-gear the axis of which corresponds to the axis of the orbital movement of the driven gear, the coupling and uncoupling of the driven gear being effected at predetermined points in its orbital movement.

One of the main features of my present invention is the employment in connection with a two-movement driven member, which will usually be of the type hereinbefore referred to of a former starter, which will control one of the movements of such driven member and will coöperate with another or resistant starter by means of which the two-movement starter, and hence the driven member, will have imparted thereto the movement just mentioned, these two starters being so constructed and coöperating with each other in such a manner that some of the working points of one starter will be disposed, and hence will operate in advance of others as the moving starter comes into contact with the resistant starter. Moreover, one of these starters should be resilient in order that the full inertia or resistance of the

moving member to be set in a state of double movement need not be overcome at the moment the two parts come in contact, but that the action of the two starters may be exerted gradually and with cumulative effect until all of the working points of the coacting faces are in contact, the object being to prevent undue acceleration of the second movement of the movable starter at the moment such second movement begins, and to maintain the two starters temporarily in engagement during the proper period to attain satisfactory results in starting the rotation of an orbitally-movable driven gear carrying types or dies which it is necessary to bring with great precision to a predetermined working point.

Ordinarily the principal features of novelty of my improved starting mechanism will be embodied in the movable starting member and not in the resistant starter—that is to say, the movable or rotary starting-arm will have a working portion some of the parts of which will be disposed in advance of others—so that the working face of the member will lie substantially obliquely to the plane of rotation of such movable starting-arm. Many different forms of starting-arms, all of which may embody the features just described, can be employed, and I have illustrated herein several different modifications, all of which illustrate this main characteristic—viz., a graduated and cumulative resistance of one part opposed to the other as the two starters come into contact with each other.

As before stated, my improved starting mechanism is intended for use in connection with key-operated mechanism of the type illustrated in my hereinbefore-mentioned patents, in which the resistant starter is usually a settable member or latch which is projected into the path of the movable starter and is afterward restored to its normal position, usually by a resetting member movable in unison with the movable starter. In the present case my improved starting-arm embodies a resetting member, both the starter and the resetter having, preferably, a resilience analogous to a torsional resilience and being oblique to the plane of rotation thereof.

Another important feature of my present improvements is the employment, in connection with a suitable carrier, of a holder for the starting-arm, which holder is adjustable on 5 the carrier to bring the working face or portion of the starting-arm to an exact predetermined position, and thus assure the proper location of the type at the moment of impression.

10 In the drawings accompanying and forming part of this specification, Figure 1 is a plan of a key-operated mechanism embodying my present improvements. Fig. 2 is a side elevation of the same with parts broken 15 away in order to illustrate the construction clearly. Fig. 3 is a transverse section of the same, the section being taken in line 3 3, Fig. 2. Fig. 4 is a partial transverse section of the same, the section being taken in line 4 4, 20 Fig. 2, illustrating certain coupling and uncoupling devices, which will be hereinafter described. Figs. 5 and 6 are enlarged sectional details illustrating in horizontal section the preferred form of my improved starting mechanism in different positions. Fig. 7 25 is an enlarged detail illustrating in sectional plan the starting-arm and its holder supported on an orbitally - movable rotary shaft. Figs. 8 and 9 are respectively front and rear 30 Fig. 2, illustrating certain coupling and uncoupling devices, which will be hereinafter described. Figs. 5 and 6 are enlarged sectional details illustrating in horizontal section the preferred form of my improved starting mechanism in different positions. Fig. 7 35 is an enlarged detail illustrating in sectional plan the starting-arm and its holder supported on an orbitally - movable rotary shaft. Figs. 8 and 9 are respectively front and rear 40 Fig. 2, illustrating certain coupling and uncoupling devices, which will be hereinafter described. Figs. 5 and 6 are enlarged sectional details illustrating in horizontal section the preferred form of my improved starting mechanism in different positions. Fig. 7 45 is an enlarged detail illustrating in sectional plan the starting-arm and its holder supported on an orbitally - movable rotary shaft. Figs. 8 and 9 are respectively front and rear 50 Fig. 2, illustrating certain coupling and uncoupling devices, which will be hereinafter described. Figs. 5 and 6 are enlarged sectional details illustrating in horizontal section the preferred form of my improved starting mechanism in different positions. Fig. 7 55 is an enlarged detail illustrating in sectional plan the starting-arm and its holder supported on an orbitally - movable rotary shaft. Figs. 8 and 9 are respectively front and rear 60 Fig. 2, illustrating certain coupling and uncoupling devices, which will be hereinafter described. Figs. 5 and 6 are enlarged sectional details illustrating in horizontal section the preferred form of my improved starting mechanism in different positions. Fig. 7 65 is an enlarged detail illustrating in sectional plan the starting-arm and its holder supported on an orbitally - movable rotary shaft. Figs. 8 and 9 are respectively front and rear

for. Figs. 34 and 35 are front and rear elevations of the starting-arm and holder shown in Fig. 32.

Similar characters designate like parts in all the figures of the drawings.

In the preferred construction my present invention will be embodied usually in a starting mechanism similar in type to that illustrated in my prior patent, No. 573,620, in which I have shown a starting mechanism 75 controlling the operation of an orbitally-movable driven gear shiftable from one to the other of two positions into and out of mesh with a driving-gear the axis of which corresponds to that of the orbit of the driven 80 gear and in which also suitable gear-shifting means controlled by the starting mechanism is employed for coupling said driven gear to the driving-gear to thereby permit the driven gear to continue rotating after it has been 85 started.

Any suitable framework may be employed for supporting the several operative parts of the mechanism, the framework illustrated in this case being indicated by A and having a 90 main shaft, such as D, carrying a rotary turret or frame, such as H, which in turn may support for rotation relative thereto a driven gear, such as 12, which driven gear is adapted to be rotated when in gear therewith by means 95 of a driving-gear—such, for instance, as the internal circular gear shown at 13. Normally the driven gear is preferably out of mesh with the driving-gear and is shiftable transversely to the plane of the driving-gear 100 into mesh therewith. This driven gear is intended in the present case to carry for movement in unison therewith one member of my starting mechanism, this movable starter or starting mechanism being indicated in the 105 construction shown in Figs. 1 to 10, inclusive, by S, said movable starter having its rotation controlled by a co-operative resistant starter which may be a latch or other suitable member interposable in the path of the movable 110 starting-arm.

A series of starters or latches constructed for interposition in the path of the starting-arm in the manner just described is illustrated herein, each being indicated by L and each being operated, preferably, by means of key-controlled connections, which may embody a spring-retracted key-lever, such as 15, connected by a short link, such as 15', to one end of a rock-arm 16', secured to a rock-shaft 16, carrying a latch-controlling rock-arm 16''. The several key-levers 15 may be mounted on a common rod 17, suitably supported on the framework, which rod may be a smooth bolt threaded for a short distance 120 from its point and the key-levers supported thereon may be separated from one another by suitable space-pieces, such as the short sleeves 18.

As before stated, one of the principal re- 130

sults sought to be attained by my present invention is the lessening of the shock or blow as the two coöperative elements of the starting mechanism come together. To secure this result, either of such starters may be constructed in such a manner as to oppose a gradually increasing or cumulative resistance to the action of the other during the starting period; but in the preferred construction I deem it desirable to embody in a movable starter the features intended to attain this end, and hence the movable starting-arm (see Figs. 1 to 10) is in this case so constructed as not only to be turned by a suitable resistant 15 starter or latch with which it comes into contact, but also is formed in such a manner as to present successive working portions thereof to such starter, which portions will oppose a gradually-increasing resistance to the action 20 of the resistant starter, and hence prevent a sudden starting of the movable starter. This starter, which is formed in the manner just described, should be resilient, and the working portion thereof will be constructed in 25 such a manner that different points in the width of the starter may have a yielding movement through paths of different lengths, whether this starter be made up of a plurality of members or elements separately resilient in paths of arcs of different lengths or 30 is a single member so shaped as to have a torsional or twisting movement substantially about the longitudinal axis of the starter.

Usually the starting-arm will embody a 35 member or face capable of resetting the resistant starter or latch by which it is turned, and in the preferred construction the rotary starting-arm will be a combined starter and resetter, both the starting and resetting portions of which will be disposed obliquely to the plane of rotation of such starting-arm, and besides will be resilient, as above described, in order to assure the opposition of a gradually-increasing resistance of the starting- 40 arm to the action of the resistant starter or latch at the moment that such arm begins rotating and also to obtain a gradual disengagement or separation of the coacting faces of the two starters on the resetting of such re- 45 sistant starter or latch.

By referring particularly to Figs. 1 to 10, inclusive, it will be seen that each movable starter S embodies a plurality of separately resilient elements s, each of which will usually 50 have both a starting portion or face, such as 26, and a resetting portion or face, such as 27, which, as the starting-arm comes into alignment with the resistant starter, exerts a toggling action upon the latter, forcing the 55 same back to its normal position, and thus resetting the same before being disengaged therefrom, this action being substantially similar to that illustrated in my last-mentioned patent.

Each of the elements s in the construction

shown in Figs. 1 to 10 will preferably be formed from steel wire, usually square in cross-section and properly shaped, each element in this case having at one of its ends an eye 28, through which a holding member may be passed and at the other end the starting and resetting portions just described. All of these elements may be of substantially similar construction; but preferably they will be so organized in a suitable holding device as to have their starting-faces lying normally in successive working positions, both circumferentially and radially of the rotary starting-arm. This will be clear by referring particularly to Figs. 7, 8, and 9, from which it will be seen that not only is the working portion of the starter oblique thereto in the direction of the width of such starter, but also depthwise thereof.

Any suitable holding means may be employed for mounting the starter just described; but in this case I have illustrated a holder or clip adapted to be secured to a rotary carrier or shaft that is journaled in the frame or turret H. In the construction illustrated this holder has in the rear side thereof a channel of such size and shape as to accommodate the several elements s of the starter S, this channel being indicated herein by 30 and having side walls which are spaced at such intervals as to hold the starter snugly in position 95 sidewise, a suitable holding device or supporting-pin, such as 31, being passed through the side walls of the channel and through the eyes 28 of the elements s to locate the latter. 100 The forward wall of the channel 30 constitutes a stop-wall for limiting the forward movements of the body portions of the elements s and is preferably so positioned and shaped that when such elements are in contact therewith they will assume the positions shown in Fig. 6, but the means for locating said elements in the other direction should be so positioned or shaped as to hold the elements normally, so that their working 105 faces will be disposed in series, as illustrated in Fig. 5. Suitable means for this purpose is indicated in said views, and particularly in Fig. 9, where I have shown a taper pin 31', passed through the side wall of the channel 30 110 and threaded into one of such walls, the taper of the body portion of this pin being such as to locate the different elements s normally in the desired successive or serial positions.

When the starter attached to the rotatable shaft is not in contact with the resistant starter, some, if not all, of the elements of the former will lie out of contact with the stop-face at their rear. Upon contact occurring and by reason of the pressing backward of each element, the length of the free portion thereof becomes shorter and shorter as it wraps around the stop-face, thus decreasing in length, and consequently increasing in stiffness with the continued movement. 130

While therefore it may be extremely flexible when first brought into action, yet with increased movement it stiffens and exerts, progressively, greater and greater resistance.

- 5 In connection with the devices just described I prefer to employ improved means for adjusting the position of the movable starter or starting-arm with respect to its carrier, and hence not only is the movable starter 10 removable from its holder for the purpose of substituting a new starter or starter element when an old one is worn or damaged, but the holder which carries such starter is also removable from its carrier and in addition is 15 adjustable relatively to the latter in such a manner as to assure an accurate location of the working portions of the starting-arm in any desired predetermined position, it being observed that an exact location of this working face is essential in order to obtain an impression of the type at the exact printing-point. Here the rotary carrier or shaft 6 is 20 cut away at certain points, as indicated at 6', to form two stop-faces, which converge, preferably, toward the axis of the shaft, and these 25 stop-faces may coöperate with other stops or holding devices for securing the holder on the shaft and locating it in its proper position. These coöperating stops will usually 30 be a pair of adjusting-screws, such as 7, the under sides of the heads of which will engage the stop-faces 6' and when both screws are tightened will draw the holder toward the shaft and will bind the two parts firmly together. When, however, one of these screws 35 is turned in and the other out, the circumferential position of the holder on the carrier or shaft 6 may be changed and the position of the starting-arm thereby correspondingly varied.
- 40 It will be noticed that each of the stop-faces 6' is disposed normally at a considerable angle to the lower face of the head of its coöperating adjusting-screw 7 and that therefore 45 a considerable circumferential adjustment of the holder may be obtained without impairing the hold of the screw upon such stop-face.

It will be noticed also that in order to provide for a considerable adjustment of the holder within limits the carrier is cut away, as shown at 6''.

In Fig. 13 I have illustrated a modification of one of the starter elements, in which an 55 element s' is made out of sheet metal and has a closed eye 28', this element being substantially similar in other respects to that hereinbefore described in detail.

In Figs. 14 to 26, inclusive, I have illustrated another type of starting-arm and holder, in which the starter and the holder by which it is carried are of different construction from the corresponding parts hereinbefore described. Here the starter is indicated 60 in a general way by S'' and, as in the former

instance, is made up of a plurality of elements, such as s'', these elements differing from the elements s and s' in that each of them has a head 28'' extending at an angle to the shank of the element instead of having an eye. The holder in the construction shown in these views differs from that illustrated in Figs. 1 to 10, inclusive, in that it embodies two main members for retaining the starter in place. One of these members is indicated 70 herein by h'' and has in the rear face thereof a deep channel 30'', substantially similar to that hereinbefore referred to; but in this case the channel 30'' is intersected by a transverse groove 31'' of such size and shape as to 75 be adapted to receive the heads 28'' of the starter elements s''. The other part of this holder is indicated by 32 and is in the nature of a keeper-plate between which and the body of the holder h'' the elements s'' may be 80 held in place, this keeper plate or tongue being so constructed as to fill the space between the side walls of the channel 30'' and being secured in position by means of a set-screw, such as 33.

It will be noticed here, and especially by referring to Figs. 19 to 21, inclusive, that the inner face of this keeper or tongue 32 is so shaped as to form proper stop-walls for holding the starter elements normally in successive or serial working positions, the stop-faces of this keeper being formed by stepped faces lying side by side and gradually diverging from one another as they approach the working end of the starting-arm.

In all of the types of the starting-arms hereinbefore described while the working portion or starting member proper of each is arranged at an angle oblique to the plane of rotation of such arm, yet in none of them are the working faces of the elements of such starter separately disposed obliquely to such plane.

In Figs. 27 and 28 a keeper-plate 32' is illustrated, having such an oblique face for 110 similarly gaging the positions of the starter elements, while in Figs. 29 and 30 a one-piece combined starter and resetter is illustrated. In this type of starting-arm the body or shank portion thereof is twisted in such a 115 manner that there will be a true torsional or twisting movement of the whole of the working end of the starter when it comes into contact with the resistant starter, whereas in those constructions in which the movable 120 starter is made of a number of separately-reliant elements the several elements thereof have no individual twisting movements. In this case the starting-arm S' has a head at its upper end by means of which it may be located or held in position.

In Fig. 31 I have illustrated another type of compound starting-arm which is made up of a plurality of members substantially similar to but preferably thinner than that shown 125

- in Fig. 29, the result being a laminated or composite starting-arm S^5 , the several elements being separated at their working ends in order that a gradually increasing or cumulative resistance may be opposed to the action of the resistant starter, as in the case of a starting-arm having a plurality of elements lying side by side. Here also the starting-arm has successively effective working portions disposed in such positions that the starter proper lies obliquely to the plane of rotation of the arm. Each of the elements of this starting-arm is twisted, as in the construction shown in Fig. 29, and the result is a composite starting-arm possessing not only a capacity for torsional yielding, but also for longitudinal flexure, and hence is much more flexible and at the same time stronger than such single-piece starting-arm.
- In Figs. 32 to 35, inclusive, I have illustrated another type of starting mechanism in which both the starting-arm and the holder are different from those hereinbefore described. Here the starting-arm S^6 is a single piece of metal, and the body portion thereof is not twisted out of the plane of the upper end of the shank; but the working end or starter proper is bent back upon the body portion of the arm and is furcated to form a plurality of starting and resetting elements or fingers lying side by side, as indicated by S^6 , these elements being preferably of different lengths and lying normally in successive or serial working positions. The parts are so organized that when engaged by a resistant starter, as shown in Fig. 33, these elements or fingers will be forced one after the other against the rear side of the body portion of the starting-arm and a gradual or cumulative resistance thus opposed to the action of the resistant starter. The holder h''' (shown in these views) differs from those hereinbefore described in several ways. In the construction illustrated it has a divided collar or clip which is held fast on the shaft 6^a by a binding-screw $33'$, which also serves to hold in place a keeper or tongue $32''$ and to bind the starting-arm in position between the keeper and the holder. Here also adjustable stops or screws are employed for locating the holder in proper circumferential position upon the shaft; but in this case said stops merely locate the holder and are not intended to clamp it in place, as in the constructions hereinbefore described. These adjustable stops or screws $7'''$ are in this construction not disposed in parallelism, but are substantially in alinement with each other, proper provision being made for a slight degree of angular movement with respect to the shaft, which will permit a considerable range of adjustment. Here the stop-faces of these screws are intended to coöperate with corresponding stop-faces 6^b on the shaft, these latter diverging as they approach the axis of the shaft instead of converging, as in the previously-described constructions.
- Any of the starting-arms or combined starters and resetters hereinbefore described may be used in connection with suitable means for continuing the rotation of such arm after its movement has been started; but in the present drawings the preferred construction (illustrated in detail in Figs. 5 to 12, inclusive) is shown in connection with such devices.
- Referring again to Figs. 1 to 6, in which I have shown in connection with my improved starting mechanism substantially the same means for continuing the rotation of the movable member of the latter as are illustrated in my prior patent, No. 573,620, it will be seen that the driven gear is fixed to a long sleeve $12'$, journaled upon the shaft 6 , so as to be capable of reciprocation thereon for the purpose of carrying the driven gear into and out of mesh with the driving-gear 13 . In order to prevent rotation of this sleeve relative to the shaft 6 , said sleeve may have a depending pin 34 , passing through an aperture in an arm or collar 35 , fixed to said shaft, this pin 34 preferably having a pair of notches into either one of which may slip a spring-pressed detent $7'$ for holding the driven gear either in or out of mesh with the driving-gear.
- The driving-gear 13 is preferably disposed so as to have its pitch-line concentric with the axis of the shaft D and will be supported in fixed alinement with a pair of cam-segments, such as 39 and 40 , each of which in this case has a cam-face inclined to the plane of the driving-gear, the longitudinal edges of these cam-faces being defined by arcs concentric with the axis of the shaft D . Each of these cam-segments constitutes in this case one member of a gear-shifting means for coupling the driven member to or uncoupling it from the driving-gear, as the case may be, the cam-segment 39 being in this case a coupling cam or member, while the segment 40 is an uncoupling-cam.
- Two gear-shifting members adapted to co-operate with the cam-segments just described are illustrated at 36 and 37 , these being supported for rotation and revolution in unison with the driven gear, the former constituting a gear-shifting coupling member or cam and the latter a gear-shifting uncoupling-cam. The cam-face of the arm 36 is inclined at an angle corresponding to that of the face of the cam 39 , while the cam-face of the arm 37 corresponds to that of the cam-segment 40 .
- As is well understood in this art, when the resistant starter or latch is interposed in the path of the movable starter or starting-arm the driven gear will be partially rotated in unison with said arm. The coupling-arm 36 is so located that as the starting-arm is engaged by the latch and said arm begins to rotate the arm 36 will be forced up the cam-face of the corresponding cam-segment 39 .

and will thereby cause the driven gear to be shifted from its normal position (out of engagement with the driving-gear) into mesh with the driving-gear, the shifting movement 5 taking place in a direction transverse to the plane of the driving or internal gear. Thereupon the detent 7' will engage the walls of the lower notch 34' in the pin 34 and will hold the gear in its upper position until such gear 10 is uncoupled.

The driven gear is normally held against rotation in a predetermined position in any suitable manner—as, for example, by means of a brake mechanism or detent device, which, 15 in the construction illustrated, embodies a holding device or spring-pressed sliding bolt, such as 19, Fig. 4, working in the bore of a tubular boss 18 on the turret or frame H, this detent being held normally in engagement with a flattened portion 12" of the sleeve 12', this flattened surface being of sufficient length to permit reciprocation of the driven gear and its connected parts.

After the commencement of the rotation of the starting-arm, and hence the driven gear 25 has been affected by a proper resistant starter or latch, the rotation of the driven gear is continued by the driving-gear until the uncoupling-arm 37 is brought into a position when 30 opposite the segment 40 by the revolving and rotating driven gear and caused to engage with the cam-surface of the segment, whereupon the force of the detent 7' will be overcome by the action of the contacting cam-faces, and the arm 37 riding down the face 35 of the segment 40 will cause the return of the driven gear to its normal position.

The main shaft D may be rotated in any suitable manner—as, for example, by means 40 of a band-wheel, such as b, around which may pass a belt, such as b', driven from any suitable source of power. Of course this shaft D will normally be rotated continuously, and hence will carry with it continuously in an 45 orbital path the driven member or gear 12 and the starting-arm moving therewith. If now any one of the resistant starters or latches L is operated by the depression of the corresponding key-lever, the starting-arm 50 will strike the resistant starter and will be partially rotated by the latter. At the moment that the coacting starters come into contact the full force required to set in motion the starting-arm S, &c., is not 55 exerted practically instantaneously, for the reason that the entire working portion of the starting-arm will not be presented all at once, but rather increment by increment to the working face of the latch, and the starting-arm 60 will not receive as violent and sudden a blow as it would if it were presented in the former way to the latch. Hence there is no rebound of the starting-arm, but a gradual rotation of the latter in true gearing engage- 65 ment with the latch and in true timing, the result of which is to cause the driven gear 12 to be carried with a uniform rotary movement into accurate and exact mesh with the adjacent portion of the driving-gear 13 without shock and without undue noise or wear. 70 Upon the parts, which, it should be noted, should, to secure the most advantageous results, be thoroughly lubricated. As the starting-arm and the latch approach their disengaging positions and when the latter 75 has been reset and the force exerted between the two relaxes said arm will not receive a sudden violent impulse, tending to accelerate its rotation before the driven gear is in proper mesh with the driving-gear; but, instead, the 80 working face of the starting member will gradually leave the resistant starter, and hence will oppose a gradually decreasing or vanishing resistance to the action of the latch, having thus no tendency to spring forward 85 and accelerate the rate of rotation of the driven gear when the resetting member leaves the working end of such latch. This action assures the even and gradual turning of the driven member into mesh with the driving 90 member, as before stated.

In the construction shown the shaft 6 carries at the upper end thereof an impression member, such as a type-wheel W, having impression faces or types t thereon, any one 95 of which may be brought opposite a suitable impression surface or plate, such as that shown at P, when the latch corresponding thereto is set by the proper key-lever, it being understood of course that each of the 100 types will be so located on the type-wheel as to move to a common *locus* in the face of the plate P when it is selected by its latch and key-lever.

Having described my invention, I claim— 105

1. The combination with a resistant starter, of a coöperative starter, one of said starters having a working portion some of the points of which are disposed in advance of others and the successive points of which working portion are adapted to come in succession into contact with a working face on the other starter.

2. The combination with a resistant starter, of a coöperative starter adapted to be conveyed periodically past the resistant starter and to have a second movement imparted to it by coöperation therewith, one of the starters being resilient in the plane of the imparted movement and one of the starters having a 110 working portion some of the points of which are disposed in advance of others.

3. The combination with a resistant starter, of a coöperative starter adapted to be conveyed periodically past the resistant starter 115 and to have a second movement imparted to it by coöperation therewith, one of the starters being resilient in the plane of the im- 120

- parted movement and one of the starters having a working face disposed obliquely to the coacting starter.
4. The combination with a resistant starter, of a coöperative starter adapted to be conveyed periodically past the resistant starter and to have a second movement imparted to it by coöperation therewith, one of the starters having successively effective resilient starting members.
5. The combination of a resistant starter and an orbitally-movable rotary starter coöperative therewith, one of said starters having a resilience analogous to a torsional resilience and having a working portion some of the points of which are disposed in advance of others.
6. The combination of a resistant starter and an orbitally-movable rotary starter coöperative therewith and having a starting member resilient in the plane of its rotary movement and the working portion of which is oblique to its plane of rotation.
7. The combination of a resistant starter and an orbitally-movable rotary starter coöperative therewith and having a working portion resilient in the plane of its rotary movement and some of the points of which are disposed in advance of others circumferentially of such starter.
8. The combination of a resistant starter and an orbitally-movable rotary starter coöperative therewith and having a working portion resilient in the plane of its rotary movement and some of the points of which are disposed in advance of others both radially and circumferentially of such starter.
9. The combination of a resistant starter and an orbitally-movable rotary starter coöperative therewith and having a working portion resilient in the plane of its rotary movement and disposed obliquely to its plane of rotation both radially and circumferentially of such starter.
10. The combination of a resistant starter and an orbitally-movable rotary starter coöperative therewith and having a multi-element starting member resilient in the plane of its rotary movement and the working portions of which are disposed in series both radially and circumferentially of such starter.
11. The combination of a resistant starter and an orbitally-movable rotary starter coöperative therewith and having a multi-element starting member resilient in the plane of its rotary movement and the working portion of which is oblique to its plane of rotation.
12. The combination of a settable resistant starter; an orbitally-movable rotary starter coöperative therewith and having a starting member resilient in the plane of its rotary movement and the working portion of which is oblique to its plane of rotation; and an orbitally-movable rotary resetting member for resetting the resistant starter.
13. The combination of a resistant starter; an orbitally-movable rotary starter coöperative therewith and having a starting member resilient in the plane of its rotary movement and the working portion of which is oblique to its plane of rotation; and an orbitally-movable rotary resetting member the working portion of which is also oblique to such plane of rotation.
14. The combination of a resistant starter; an orbitally-movable rotary starter coöperative therewith and having a member resilient in the plane of its rotary movement the working portion of which is oblique to its plane of rotation; and a similarly resilient orbitally-movable rotary resetting member the working portion of which is also oblique to such plane of rotation.
15. The combination of a resistant starter and a resilient orbitally-movable rotary combined starter and resetter coöperative therewith and having its starting and resetting portions oblique to its plane of rotation.
16. The combination of a resistant starter and a resilient orbitally-movable rotary combined starter and resetter coöperative therewith and having substantially parallel starting and resetting portions disposed obliquely to its plane of rotation.
17. The combination of a resistant starter and an orbitally-movable rotary combined starter and resetter coöperative therewith and having a starting and resetting member resilient in the plane of the rotary movement.
18. The combination of a resistant starter and an orbitally-movable rotary combined starter and resetter coöperative therewith and having a multi-element starting and resetting member resilient in the plane of the rotary movement.
19. The combination of a resistant starter and an orbitally-movable rotary combined starter and resetter coöperative therewith and having a starting and resetting member resilient in the plane of the rotary movement disposed obliquely to its plane of rotation.
20. The combination of a resistant starter having a convex end, and an orbitally-movable rotary combined starter and resetter coöperative therewith and embodying a resilient socket disposed obliquely to the plane of the rotary movement having starting and resetting walls.
21. The combination of a resistant starter having a convex end, and an orbitally-movable rotary combined starter and resetter coöperative therewith and embodying a resilient multi-element socket disposed obliquely to the plane of the rotary movement having starting and resetting walls.
22. The combination of a resistant starter and a movable starter coöperative therewith,

one of said starters embodying a plurality of starter elements separately resilient in the path of the movable starter.

23. The combination of a resistant starter 5 and an orbitally-movable rotary starter co-operative therewith and embodying a plurality of starter elements separately resilient in such path of rotation.

24. The combination of a resistant starter 10 and a revolute rotary starter co-operative therewith and embodying a plurality of starter elements separately resilient in such path of rotation.

25. The combination of a resistant starter 15 and an orbitally-movable rotary starter co-operative therewith and embodying a plurality of resilient starter elements separately movable from end to end thereof in such path of rotation.

26. The combination of a resistant starter 20 and an orbitally-movable rotary starter co-operative therewith and embodying a plurality of resilient starter elements disposed side by side and separately movable in such path of rotation.

27. The combination of a resistant starter and an orbitally-movable rotary starter co-operative therewith and embodying a plurality of resilient starter elements disposed 30 side by side and separately movable from end to end thereof in such path of rotation.

28. The combination of a driving-gear; an orbitally-movable driven gear normally out of mesh therewith and movable in the orbit 35 of the driving-gear; a resistant starter and a co-operative rotary starter orbitally movable in unison with the driven gear, one of said starters having a working portion constructed to oppose a gradually-increasing or cumulative 40 resistance to the other as the two come into contact, and thereby rotate the driven gear in true timing as it meshes with the driving-gear; and gear-coupling means controlled by the rotation of the driven gear.

29. The combination of a driving-gear; an orbitally-movable driven gear normally out of mesh therewith and movable in the orbit of the driving-gear; a resistant starter; a co-operative rotary starter orbitally movable 50 in unison with the driven gear and having a working portion constructed to oppose a gradually-increasing or cumulative resistance to the resistant starter as the two come 55 into contact, and a gradually decreasing or vanishing resistance as they separate, and thereby rotate the driven gear in true timing as it moves into mesh with the driving-gear; and gear-coupling means controlled by the 60 rotation of the driven gear and operative for shifting the latter into mesh with the driving-gear.

30. The combination, with a rotary carrier having a pair of separated stop-faces, of 65 a holder mounted on said carrier, and a pair

of adjustable stops carried by said holder and adjustable in opposite directions transversely to the axis of the carrier and into engagement with said stop-faces, to thereby adjust the holder circumferentially of said 70 carrier.

31. The combination, with a rotary carrier having a pair of separated stop-faces, of a holder mounted on said carrier, and a pair of adjusting-screws carried by said holder 75 and adjustable in opposite directions transversely to the axis of the carrier and into engagement with said stop-faces, to thereby adjust the holder circumferentially of said carrier. 80

32. The combination, with a rotary carrier having a pair of separated stop-faces, of a holder mounted on said carrier, and a pair of adjusting-screws carried by said holder and adapted to engage the under sides of the 85 heads of said stop-faces, and adjustable in opposite directions transversely to the axis of the carrier to thereby adjust the holder circumferentially of said carrier.

33. The combination, with a rotary carrier having a pair of separated stop-faces converging toward the axis thereof, of a holder mounted on said carrier, and a pair of adjustable stops carried by said holder and adjustable in opposite directions transversely 95 to the axis of the carrier and into engagement with said stop-faces, to thereby adjust the holder circumferentially of said carrier.

34. The combination, with a rotary carrier, of a holder on said carrier and having 100 guide-walls, and a removable starting-arm carried by said holder and guided by said guide-walls.

35. The combination, with a rotary carrier, of a channeled holder on said carrier, 105 and a removable starting-arm seated in said channel.

36. The combination, with a rotary carrier, of a channeled holder on said carrier; a removable starting-arm seated in said channel and embodying a plurality of separately-resilient similar elements lying side by side; and a taper pin intersecting the side walls 110 of said channel in the holder, to thereby locate the elements of the starting-arm normally in successive working positions.

37. The combination with a resistant starter, of a movable combined starter and resetter co-operative therewith, the combined starter and resetter having a working 120 portion some of the points of which are disposed in advance of others and the successive points of which working portion are adapted to come in succession into contact with a working face on the other starter. 125

38. The combination with a resistant starter, of a combined starter and resetter co-operative therewith and adapted to be conveyed periodically past the resistant-starter and to have a rotary movement imparted to 130

it by coöperation therewith, the combined starter and resetter having its working face, as measured transversely to the plane of rotation, oblique to such plane.

5 39. The combination with a resistant starter, of a movable combined starter and resetter coöoperative therewith and adapted to be conveyed periodically past the resistant starter and to have a second movement im-
10 parted to it by coöperation therewith, the combined starter and resetter having a working portion some of the points of which are disposed in advance of others and the suc-
15 cessive points of which working portion are adapted to come in succession into contact with a working face on the other starter.

40. A shaft-starting arm for initiating the rotary movement, of an orbitally-moving shaft, said arm having a working face some 20 of the points of which are disposed in advance of the others and the successive points of which working portion are adapted to come in succession into contact with a working face on the other starter.

25 41. A shaft-starting arm for initiating the angular movement of a shaft, arm having starting-faces adapted to engage one after another.

30 42. A shaft-starting arm for initiating the rotary movement of an orbitally-moving shaft, said arm having its working face, as measured transversely to the plane of rotation, oblique to such plane.

35 43. A shaft-starting arm for initiating the rotary movement of an orbitally-moving shaft, said arm having a working portion re-
silient in the plane of the rotary movement.

40 44. A shaft-starting-arm for initiating the rotary movement of an orbitally-moving shaft, said arm having a working portion re-
silient in the plane of the rotary movement, and an oblique starting-face.

45 45. A shaft-starting arm for initiating the rotary movement of an orbitally-moving shaft, said arm having a multi-element working portion, and an irregular starting-face.

46. A shaft-starting arm for initiating the rotary movement of an orbitally-moving

shaft, said arm having a multi-element working portion resilient in the plane of the rotary movement, and an irregular starting-face.

47. The combination with settable resistant starters, of a member adapted to be conveyed periodically past the resistant starters, and a movable starter for coöoperating 55 with a set resistant starter and initiating a second movement of the said member, said movable starter embodying an element brought into contact with the working face of the resistant starter progressively along 60 the length thereof during the action of the starters.

48. The combination with a starter, of a coöoperative starter, one of said starters having a working portion some of the points of 65 which are disposed in advance of others and the points of which working portion are adapted to come in succession into contact with a working face on the other starter.

49. The combination of a resistant starter 70 having a number of working points some of which are disposed in advance of others of said points, and the points adapted to come in succession into contact with the other starter.

50. A shaft-starting arm for initiating the angular movement of a shaft, said arm having a plurality of starting-faces located and arranged to become active after the other.

51. A shaft-starter for initiating the ro- 80 rotary movement of a shaft, said arm having its working face, as measured transversely to its rotation, oblique to such transverse plane.

52. A shaft-starting arm for initiating the angular movement of a shaft, said arm being effective successively in a plurality of angular positions.

53. A shaft-starting arm for initiating the rotary movement of an orbitally-movable 90 shaft, said arm having a working portion resilient in the plane of its working movement.
